UNITED STATES PATENT OFFICE.

ABRAHAM V. CROSS, OF WILLIAMSPORT, PENNSYLVANIA.

CUTTER-HEAD.

SPECIFICATION forming part of Letters Patent No. 275,890, dated April 17, 1883.

Application filed January 3, 1883. (No model.)

To all whom it may concern:

Be it known that I, ABRAHAM V. CROSS, of 5
Williamsport, Lycoming county, Pennsylvania, have invented a new and useful Improvement
in Cutter Heads and Knives for Rotary
Planers, of which the following is a full, clear,
and exact description.

My invention relates to improvements in
the cutter heads and knives of rotary planers;
10 and it consists in the peculiar construction and
arrangement of the parts, as hereinafter more
fully set forth.

Reference is to be had to the accompanying
drawings, forming a part of this specification,
15 in which similar letters of reference indicate
corresponding parts in all the figures.

Figure 1 represents a partially sectional end
view of the cutter-head of a rotary planer with
my improved cutter or cutters and means of
20 adjusting and securing the same applied. Fig.
2 is a top or face view of the same with one of
the knife-holding taps or back plates removed,
and Fig. 3 an under or inner face view of one
of said plates detached.

25 The cutter-head A, which may have any
number of knife-carrying wings or faces b, is
represented as constructed for and carrying
knives or cutters which have their cutting-
edges arranged so as to cut at all points si-
30 multaneously throughout their length, as in
what are known as "straight planers;" but
said parts may be constructed and arranged
to give an oblique or gradual cut, as in vari-
ous kinds of diagonal planers. As hereinbe-
35 fore observed, each wing b may have any num-
ber of knives or cutters of different patterns
arranged side by side on them. For the pur-
poses of illustration, each wing b is here shown
as carrying two straight-edged knives, B B',
40 and an intermediate beading cutter or knife, C,
arranged so that each succeeding row of cut-
ters breaks joint with the preceding row there-
of by making the knives B B' of different
lengths on their cutting-edges and arranging
45 a long knife in the one row in advance or in
rear of a short knife in the next or a following
row, whereby ridges on the cut surface are
prevented, and the knives are prevented from
getting out of balance. If desired, there may
50 be any number of cutter-heads A thus armed
with knives or cutters arranged upon the same
shaft, and the knives may be of any desired

length or size. In some cases each wing b may
carry only a single knife or cutter. Each of
said knives or cutters B B' or C, which may 55
be of one-eighth of an inch thickness, (more or
less,) has formed in its back a series of V or
othersuitably shaped parallel grooves, c, across
or along it, and is held in its place on the wing
b of the rotary head which carries it by a 60
steel or other suitable back or lapping plate,
D, that is constructed on its inner face with a
rib or tooth, d, corresponding to either groove
c, and interlocking therewith to hold the sev-
eral cutters on the same wing in position. 65
These plates D are secured to the cutter-head
A by a screw, e, arranged to pass through an
oblong slot, f, in each of said plates, which is
in transverse relation to the grooves c and rib
d, and in rear of the knives or cutters B B' C, 70
whereby the lapping plate D may be adjusted
forward or backward, as required, to meet
wear or other changes of the cutters.

By means of the grooves c in the backs of
the knives, and the engaging rib d in the in-
ner face of either lapping plate D, the knives
or cutters may be adjusted in or out, with their
75 cutting-edges always in parallel relation with
the cutter-head. Furthermore, said knives
or cutters are made with opposite cutting-
edges, g, whereby the knives, when worn too
80 much on their one edge, may be reversed or
turned end for end, thus utilizing the knife to
its fullest extent.

By this construction and arrangement of 85
parts not only may the knives be reversed, as
described, and be set in or out, as required, by
making the rib d of the plate D to engage
with either groove c in the backs of the knives,
but where a beading-cutter, C, is used the 90
knives may be moved longitudinally on the
cutter-head and in different positions in or
out relatively to the lapping plates D, as the
molding or cut to be made requires. These
95 adjustments are not provided for in the usual
solid cutter-head. All the sharpening of the
knives may be done by filing instead of grind-
ing, and the knives may be almost completely
used up before discarding them as worn out,
the reversing of the knives, in addition to their
100 adjustment backward or forward by the grooves
c and the rib d, giving an enlarged advantage in
this respect. Either knife or cutter may be so
adjusted or reversed independently of the other.

Having thus described my invention, I claim as new and desire to secure by Letters Patent—

The combination, with the cutter-head A, provided with wings b, of the reversible cutters B B' C, having parallel grooves c on their backs, and their cutting - edges of different lengths, so that the cutters on one wing may overlap the joints on the succeeding wing,

holding-plates D, each provided with a rib, d, and slot f, and screw-bolts e, substantially as described, and for the purposes set forth.

ABRAHAM V. CROSS.
